US00D725356S

(12) **United States Design Patent**
Miner

(10) **Patent No.:** **US D725,356 S**
(45) **Date of Patent:** ** *Mar. 31, 2015

(54) **SHOE SOLE**

(71) Applicant: **NIKE, Inc.**, Beaverton, OR (US)

(72) Inventor: **Mark C. Miner**, Portland, OR (US)

(73) Assignee: **NIKE, Inc.**, Beaverton, OR (US)

(*) Notice: This patent is subject to a terminal disclaimer.

(**) Term: **14 Years**

(21) Appl. No.: **29/492,565**

(22) Filed: **May 31, 2014**

Related U.S. Application Data

(63) Continuation of application No. 29/481,800, filed on Feb. 10, 2014, now abandoned, which is a continuation of application No. 29/465,636, filed on Aug. 29, 2013, now abandoned, which is a continuation of application No. 29/443,440, filed on Jan. 17, 2013, now abandoned, which is a continuation of application No. 29/429,338, filed on Aug. 9, 2012, now abandoned, which is a continuation of application No. 29/414,576, filed on Feb. 29, 2012, now abandoned.

CLAIM

The ornamental design for a shoe sole, as shown and described.

DESCRIPTION

FIG. 1 is a front perspective view of a shoe sole showing my new design;

FIG. 2 is a lateral side view thereof;

FIG. 3 is a medial side view thereof;

FIG. 4 is a front view thereof;

FIG. 5 is a rear view thereof; and,

FIG. 6 is a top view thereof.

The broken lines showing the remainder of the shoe are for environmental purposes only and form no part of the claimed design.

1 Claim, 5 Drawing Sheets
